UNITED STATES PATENT OFFICE

FREDERICK S. SCHWINN, OF HOUSTON, TEXAS

UNIVERSAL ANCHOR PLATE

Application filed April 20, 1931. Serial No. 531,480.

My invention relates to anchor plates for use in fixing rails to the cross ties in railroad construction.

It is an object of the invention to provide an anchor plate which is adapted for universal use so that it may serve as a support for all common sizes of rails which may be employed in road building.

It is a further object of the invention to provide means in connection with the anchor plate which is easily adjustable to engage with any of the ordinary sizes of rails without difficulty and which when fixed in position will firmly anchor the rail to the cross ties.

I desire to provide an anchor plate which may be used with cross ties of all ordinary constructions and which will protect the tie from rail wear.

The invention also includes the provision of cam plates which are readily adjustable and which are provided with clamping rims thereon which engage the base of the rail so as to obtain a comparatively large frictional contact with the rail when said plates are anchored in position.

In the drawings herewith Fig. 1 is a transverse section through a rail showing the same supported and anchored in position with my improved anchor plate.

Fig. 2 is a top plan view of the anchor plate with a section of rail supported thereon.

It is to be understood that my base plate 1 is adapted to be supported upon any type of cross tie. The plate is shown as rectangular in shape having adjacent its ends a plurality of openings therein to receive spikes 2. Said spikes may be of proper construction to fix the plate to the particular cross tie which is employed.

They may be steel cut track spikes, or, as is shown in the drawings, they may be screw spikes or bolts adapted to be screwed through the openings in the plate into the cross tie and anchor the plate firmly in position. Washers 3 below the heads of the spikes are preferably employed.

The plate 1 is preferably provided with a pair of upwardly extending bosses 4 spaced apart a sufficient distance to include between

them the base 5 of any size of rail 6, and to allow the mounting on said bosses of clamping plates 7. Said bosses are tapered slightly toward the upper face thereof and are formed with axial openings 8 therethrough to receive bolts 9 adapted to anchor the plates in position.

The cam plates 7 are formed with recesses 10 on the lower side thereof to fit upon the bosses 4 and to be rotatable thereon. The central portion of the cam plate is formed with an upwardly extending hub 11 thereon to engage about the anchor bolts 9. The openings 12 through said plates are arranged eccentrically relative to the plates so that when the said plates are rotated about the bosses 4 the outer peripheries 13 thereof may be adjusted to engage against the adjacent edges of the rail base 5. The said plates are formed with radially extending rims 14, which are beveled slightly on the lower side, as shown at 15, to engage with the upper surface of the rail base. It will thus be seen that when the cam plates 7 are mounted upon the bosses with the bolts 9 extending upwardly therethrough they may be rotated to bring the outer periphery thereof in clamping engagement with the rail plate and that they can be readily adjusted for various widths of rail base. In the drawings the cam plates are shown, as engaging with the base of the narrowest type of rail. Wider rail bases can be readily accommodated by a slight rotation of the cam plates upon the bolts 9 as an axis.

The bolts 9 are fitted within the openings 8 in the base plate, said openings being countersunk at 16 to receive the heads 17 of the bolts. The upper ends of the bolts are provided with nuts 18 and lock washers 19 thereon.

The operation of my device will be readily understood. The base plates 1 may be anchored in position upon the cross ties with the bolts 9 extending upwardly through the openings 8 in the bosses 13. The rail may then be placed in position upon the base plate and the cam plates 7 placed in position and rotated until the outer periphery thereof engages firmly against the rail base. The nuts 18 with lock washers 19 thereon will then be employed to clamp the cam plates 7 rigidly.

in position, anchoring the rail firmly against movement.

It will be obvious that this anchoring device may be quickly adjustable so as to firmly anchor the rail in position. It is also obvious that with this type of rail anchoring device the gauge of the track may be changed slightly with very little adjustment of the anchoring device. Furthermore, it is possible to substitute one width of rail for another by a very slight adjustment of the cam plates as has been described. The particular anchor plate will be seen to have a wide engagement with the rail base which will tend to clamp the rail in position more effectively than with the usual spikes. This will tend to eliminate creeping of the rail relative to the plate and minimizes mechanical wear between the plate and the rail. This type of anchor also overcomes the effect of rail expansion under heat as a factor in track construction. It has other advantages which will be obvious to those skilled in the art.

What I claim as new is:

25 A combined tie plate and rail anchor including an oblong plate shaped to fit upon a cross tie, said plate being adapted to support a rail midway between its ends, bosses on said plate on opposite sides of said rail, cam shaped plates mounted rotatably on said bosses, a rim on each of said cams and means to clamp said cam plates upon rails of various widths.

30 In testimony whereof I hereunto affix my signature this 10th day of April A. D. 1931.

FREDERICK S. SCHWINN.
